(57) **CLAIM**

The ornamental design for a HiFi system, as shown and described.

DESCRIPTION

The claimed HiFi system is used for reproducing sound with high fidelity.

FIG. 1 is a front elevational view of a HiFi system showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken line showing of the HiFi system is included for the purpose of illustrating environmental structure and forms no part of the claimed design.
